UNITED STATES PATENT OFFICE.

JOHN S. ANDERSON, OF ST. LOUIS, MISSOURI, ASSIGNOR TO NORTH & JUDD MANUFACTURING COMPANY, OF NEW BRITAIN, CONNECTICUT, A CORPORATION OF CONNECTICUT.

BREAST-STRAP SLIDE AND ATTACHMENT.

No. 809,927.

Specification of Letters Patent.

Patented Jan. 16, 1906.

Application filed July 22, 1905. Serial No. 270,748.

To all whom it may concern:

Be it known that I, JOHN S. ANDERSON, a citizen of the United States, residing at St. Louis, Missouri, have invented certain new and useful Improvements in Breast-Strap Slides and Attachments, of which the following is a full, clear, and exact description.

My invention relates to improvements in harness-fittings, and particularly to a breast-strap slide.

The object of the invention is to provide a simple and reliable device for a breast-strap for connecting it to a pole-piece or chain so that the parts may freely take up any position which they may be called upon to take up in ordinary use without friction or binding or undue wear on the parts.

The invention consists in improvements the principles of which are illustrated in the accompanying single sheet of drawings.

Briefly, it comprises a member having depending ears, to which is pivoted a block carrying a snap-hook, all three of the parts being freely movable with relation to one another.

The details will be more clearly understood from the following specification:

Figure 1 is a side view of a device embodying the improvements of my invention. Fig. 2 is a front view thereof. Fig. 3 is a view similar to Fig. 1, but showing the slide, body, block, and snap-tongue in section.

1 indicates an arched portion of the slide to which the breast-strap is attached.

2 and 3 are side flanges or ears depending from the arched portion and preferably enlarged or reinforced at the lower end.

4 and 5 are end pieces which connect the side flanges and serve as guides and guards for the strap.

6 is a pin, preferably upset or headed, on the outer faces of the flanges 2 and 3.

7 is a solid block pivotally mounted on the pin 6 and having an eye with rounded edges for the attachment of the snap-hook. 45

8 is the body of the snap-hook.

9 is the eye secured in the eye of the block 7.

10 is the bill of the hook.

11 is the tongue of the hook, pivoted to the body 8, normally held in position by the pressure of the spring 12, as shown in Fig. 3. 50

All of the parts are heavily made, so as to withstand great strains, and so secured together that the greatest freedom of movement is possible without causing undue friction. 55

The advantages of this construction will be apparent to those who are skilled in this art.

What I claim is—

1. A breast-strap slide comprising a body having an arched portion 1, depending flanges 2 and 3, end pieces 4 and 5, a headed pivot-pin 6, and a solid or block 7 pivoted on said pin and having an eye with rounded edges 65 for the swinging attachment of a snap-hook or other device.

2. A breast-strap slide comprising the combination of a body having an arched portion 1 and the side flanges 2 and 3, a pivot-pin 6 70 carried by the side flanges, a solid block 7 pivotally mounted on said pin, and a fastener having an eye 9 loosely hung in the eye of said block so as to permit it to swing freely back and forth and from side to side.

JOHN S. ANDERSON.
